UNITED STATES PATENT OFFICE.

WILLIAM H. NUNAMACHER, OF NEWARK, NEW JERSEY.

FREIGHT-CAR.

No. 874,615.

Specification of Letters Patent.

Patented Dec. 24, 1907.

Application filed September 11, 1907. Serial No. 392,271.

To all whom it may concern:

Be it known that I, WILLIAM H. NUNAMACHER, a citizen of the United States, residing in the city of Newark, in the county of 5 Essex and State of New Jersey, have invented certain new and useful Improvements in Freight-Cars, of which the following is a full, clear, and exact description, such as will enable others skilled in the art to which it pertains to make, construct, and use the same.

In the present construction of box cars, entire reliance is placed upon the frame work of the car to prevent distortion and the breaking out of the ends of the car, due to 15 the shifting of the load. It frequently happens in shunting cars laden with dressed lumber, heavy package freight, and the like, that when such car is suddenly stopped, as coming in contact with another car, or with the 20 bumper at the end of the side track, the momentum of the lumber, package freight and the like, is such that it will shift longitudinally of the car and break through the end, while frequently this sliding motion of the 25 freight, if insufficient to break the end of the car, will so rack the frame as to necessitate the sending of the car to the repair shop, where it is frequently out of commission of from two weeks to two months.

My invention has for its object, to so strengthen and brace the frame work of the car that the above named difficulties will be completely obviated, and while my improvements are of such a nature as to make them 35 readily applicable to new cars, yet they can as readily be applied to cars already in use.

In carrying out my invention, I make use of the structures illustrated in the accompanying drawings, which show merely the essential timber work of the car, omitting the 40 side trusses and braces usually present.

The improvement consists in the series of metallic braces in connection with a sheet-metal car end.

Figure 1 illustrates a top plan view of the frame work of a car illustrating the roof brace and end wall braces. Fig. 2 is a side view of the same. Fig. 3 is a longitudinal section on line $x-x$ of Fig. 2. Fig. 4 is a 50 cross-section on line $y-y$ of Fig. 1, and Fig. 5 is a side view of the carline hereinafter referred to.

Similar letters of reference refer to like parts throughout the specification and drawings.

As above stated, only the essential ele-

ments of the frame work of the box car are illustrated in the drawings.

1 is the top chord, 2 the door jamb, and 3 the side car sill.

60

4 is the longitudinal center sills.

5 is the corner post, connecting the end side sills 3 with the top chord.

6 is a longitudinal girth extending between the end post 5 and the door jamb 2.

65

7 is the top end chord connecting the top chords 1.

The elements thus described are of the usual and ordinary construction.

I have omitted from the drawings the other wooden braces which are usually present in the frame work of a box car, the omission being for the purpose of clearness.

Completely spanning the end of the car from the top chord to the sills and from side to 75 side, is the large sheet-metal plate 8, located inside of the end timbers, and secured in position by means of bolts. Running diagonally on each side of the car between the upper end of the corner post 5 and the lower end 80 of the door jamb 2, is the metallic brace 9, the upper end of which is bent around and extends between the upper corners of the plate 8 and the end chord 7, as clearly shown in Fig. 1. The lower end of the brace 9 extends beneath the sill 3 and is lapped around 85 the under side and bolted in position.

Connecting the lower edge of the plate 8 with the longitudinal car sills is the angle bar 10, running completely across the lower edge 90 of the plate and the car sills. The angle plate 10 is rigidly secured to the plate 8 and to the car sills 3 and 4 by means of bolts or rivets 11 as shown.

Extending across between the end posts 5 95 is the end girth 12 located at the same height as the girths 6. Outside of the girth 12 I locate the tension bar 13, the ends of which lap around the corners of the car as illustrated in Fig. 3, and are secured to the girths 6 by 100 means of the bolts 14. The middle portion of the tension bar 13 is cambered away from the girth 12 and between such bar and the girth 12, I locate the strut 15. In this manner, I form a very rigid truss for the middle portion 105 of the end of the car.

Between the plate 8 under the end girth 12, I locate the middle portion of the long U-shaped brace 16, the arms of which extend along on the inside of the girth 6 with their 110 extremities lapped around the door jambs 2 to which they are secured by means of bolts.

With the braces 9, 13 and 16 in position, in connection with the end plate 8, I have provided effective means for preventing the load of the car from shifting longitudinally to such an extent as to break out the end of the car, or so rack the car frame as to render it useless. The strains due to the sudden stoppage of the car and the inertia of the load are effectually resisted by the two braces 9 and 16.

10 In order to form an effective brace for the upper end chord 7, I provide the following structure: Between the upper chords 1 and 2 located midway of the car body, I provide the tubular carline 17 clearly shown in cross-section in Fig. 4. This carline is made from sheet metal rolled up so as to form the lower tubular compression member 18, with the fin members 19 shaped to conform substantially with the inclines of the roof. Portions 20 of the fins 19 are cut down and bent outwardly as at 20 to receive the longitudinal roof timbers 21. The ends of the carline are splayed outwardly so as to lie parallel with the top chord and are secured to such top 25 chords by means of the eye-bolts 22. Running diagonally from the eye-bolts 22 to the middle of the end top chord 7 are the diagonal braces 23, the forward ends of such rods running through castings 24 and 25, which have 30 inclined faces, perpendicular to the axis of such rods 23, so that nuts 26 may be threaded upon the rods 23 and form an easy means of adjusting the tension in such rods. Without the diagonal brace 23, there might be a 35 tendency for the top chord to fracture under heavy stresses; the braces 23, however, being connected from each end of the car to the middle to the top chords will effectually obviate this tendency.

40 In Figs. 1, 2 and 3, I have illustrated about half of the car frame. It will be understood, however, that the braces, end plate and tension members are to be applied to the opposite end of the car in the same manner as 45 illustrated, so that both ends of the car will be braced alike.

Changes may be made in the form of structure of the several braces to suit the different conditions under which they are used; for 50 example, the carline 17 may be of any other structure than that illustrated, as a plain cross piece of timber to act as a spreader to prevent the two top chords from drawing together under the longitudinal strain produced by the rods 23. Again, the U-shaped braces 16 may be divided and extend only from the end girth 12 to the jamb 2, the outer end being bent around beneath the plate 8 for a short distance upon the girth 12. The 55 plate 8 is of substantial thickness and being of tough steel, will not fracture under the heavy strains to which car ends are subjected, while the diagonal braces 23 serve to prevent any racking or distortion of the car 60 frame.

It will be seen that braces and end plates are as readily applicable to cars in present use as to new cars.

I claim:

1. In a box car, the combination with the top and end chords and the sills of the car body, of a metallic end plate spanning the end of said body and secured to said chords and sills.

2. In a box car, the combination with the 75 timbers of the car body, of a metallic plate secured within the car to the end timbers, and diagonal metallic braces extending from the upper corners of said plate to the side 80 sills.

3. In a box car, the combination with the corner posts, end and side sills of a car body, of a metallic plate covering the end of the car, and secured to said posts and sills, and a pair of metal braces secured to the upper 85 corners of said plate and extending diagonally and secured to said side sills respectively.

4. In a device of the class described, the combination with the side and end sills and top end chord of a car body, of a metallic end plate within said body and secured to said sills and top chord, a pair of tension 90 braces connected at their upper ends respectively to the upper corners of said plate 95 and extending diagonally downward and secured to the side sills approximately midway of their length.

5. In a device of the class described, the combination with the usual timbers of a car 100 body, of a metallic plate secured to and covering the end of said body upon its inside, a metallic brace secured at one end to the door jamb of the car body, and extending parallel with the side girth of said body and 105 having its opposite end secured between the end girth and said metallic plate.

6. In a device of the class described, the combination with side and end sills, the top end chord, and the side and end girths of a car 110 body, of a metallic plate covering the inside end of said body, a pair of diagonal metal braces connecting the upper corners of said plate and said side sills approximately midway of their length, and a U-shaped brace 115 having the arms thereof secured to the side girths and its middle portion secured between said plate and the end girth.

7. In a box car, the combination with the usual timbers of the car body including the upper side and end chords, of a metallic plate located within and secured to the end of said body, a carline located midway of and secured to said upper side chords, and a pair of metallic tension braces secured at their inner ends to the ends of said carline respectively, and their opposite ends secured to said plate and upper end chord.

8. In a box car, the combination with the usual timbers of the car body including the 130

- upper side and end chords, of a metallic plate located within and secured to the end of said body, a carline located midway of and secured to said upper side chords, and 5 a pair of metallic tension braces secured at their inner ends to the ends of said carline respectively, their opposite ends secured to said plate and upper end chord and means for adjusting the tension of said braces.
- 10 9. In a box car, the combination with the usual timbers of a car body, of means for strengthening the end of said body, comprising a metallic plate covering and secured to the end of said body upon the inside, a 15 pair of tension braces extending diagonally from the upper corners of said plate to approximately the middle of the side sills, a U-shaped brace having its arms secured to the side girths and door posts and its central 20 portion located between and secured to said plate and the end girth, a carline located midway of and secured to the upper side chords, and a pair of tension braces connecting the ends of said carline with the middle of the 25 upper end chord.
10. In a box car, the combination with the usual timbers of a car body, of means for strengthening the end of said body, com-
- prising a metallic plate covering and secured to the end of said body upon the inside, a 30 pair of tension braces extending diagonally from the upper corners of said plate to approximately the middle of the side sills; a U-shaped brace having its arms secured to the side girths and door posts and its central 35 portion located between and secured to said plate and the end girth, a carline located midway of and secured to the upper side chords, and a pair of tension braces connecting the ends of said carline with the middle of the 40 upper end chord and means for adjusting the tension of said tension braces.
11. In a box car, the combination with the end posts and girth of a car body, of a metallic plate spanning the end of said body, and secured to said girth, of a brace for said plate comprising a cambered tension member having its ends secured to said posts and a strut between its middle portion and said end girth. 45

This specification signed and witnessed 50 this 3rd day of September, 1907.
